UNITED STATES PATENT OFFICE.

IRA L. FRENCH, OF CHICAGO, ILLINOIS, ASSIGNOR TO THE MANTLE LAMP COMPANY OF AMERICA, OF CHICAGO, ILLINOIS, A CORPORATION OF ILLINOIS.

DESIGN FOR A SERVING-DISH.

56,744.

Specification for Design.

Patented Dec. 14, 1920.

Application filed February 28, 1920. Serial No. 362,128. Term of patent 14 years.

To all whom it may concern:

Be it known that I, IRA L. FRENCH, a citizen of the United States, residing at 4434 Sidney avenue, Chicago, in the county of Cook and State of Illinois, have invented a new, original, and ornamental Design for Serving-Dishes, of which the following is a specification, reference being made to the accompanying drawing, forming a part thereof.

Figure 1 shows the dish in elevation; and

Fig. 2 is a top plan view of said dish.

The dish is circular and shallow, but its precise form may be varied provided the design thereof is retained.

I claim:

The ornamental design for a serving dish, as shown.

IRA L. FRENCH.
